HOLDER FOR RAZOR BLADES

Paine Lee Bush, Dallas, Tex.

Application August 21, 1935, Serial No. 37,240

2 Claims. (Cl. 30—162)

This invention relates to blade holders and more particularly to devices for utilizing and holding razor blades for uses other than shaving and after their utility as razor blades has passed and it consists in the combinations, constructions and arrangements herein described and claimed.

It is an object of the invention to provide a device of this kind in which the holder for the blade is provided with a clamp which forms part of the gripping part of the device and which, upon the application of the natural grip of the user's hands, will tend to hold the blade more securely in proportion to the pressure of the grip.

It is a further object of the invention to provide a device of the character described above which may be made so compact as to be usable as a watch charm.

It is a further object of the invention to provide a device of this character which may be made of comparatively cheap metal yet which will provide great strength and durability.

A still further object of the invention is the provision of means whereby a blade may be gripped very securely, yet may be released or adjusted immediately upon releasing the pressure upon the clamp referred to above.

Another object of the invention is to provide a device of this kind which will be entirely free from set screws, slides, flanges and loose and dangling parts; which will be cheap to manufacture and will be simple in construction and operation.

Other objects and advantages will appear in the following specification, forming part of this application, and the novel features of the device will be particularly pointed out in the appended claims.

The invention is illustrated in the accompanying drawing, forming part of this application, in which

Figure 1 is a side elevational view of one form of the invention, showing the device in inoperative or closed position.

Figure 2 is a similar view, but showing the device in open or operative position.

Figure 3 is a similar view, partly in section, showing a clamp, later to be discussed, in disengaged position.

Figure 4 is an enlarged sectional view taken substantially along line 4—4 of Fig. 2.

Figure 5 is a side elevational view of another form of the invention in closed position.

Figure 6 is a similar view to Fig. 5 showing the device in open position.

Figure 7 is a view similar to Fig. 5, showing a

clamp, later to be described, in inoperative position.

Figure 8 is an enlarged sectional view taken substantially along line 8—8 of Figure 5.

Figure 9 is a side elevational view of still another form of the invention in closed position.

Figure 10 is a similar view to Fig. 9 showing the device in operative position, and

Figure 11 is a perspective view of the device shown in Figs. 10 and 9 with a clamp, later to be described, in disengaged position.

In the following description wherein reference to the drawing is made more particularly, the same reference characters are utilized for similar parts in the various modified forms of the invention.

In Figs. 1 to 3, there is shown a blade holder 10 of resilient metallic construction and having an enlarged portion at the top thereof as indicated at 11 and being so shaped as to snugly fit around a razor blade 12 of conventional structure. It will be seen that the blade 12 is slidable longitudinally of the holder.

Pivotedly mounted and overlapping the lower ends of the holder 10 by means of a rivet 13 or the like is a U-shaped clamp 14, which, when in its uppermost position, as shown clearly in Figs. 1 and 2, causes a contracting of the sides of the holder 10 and a consequent gripping of the blade 12 therebetween. This clamping action takes place due to the fact that the clamp is formed of a comparatively rigid metal, while the holder is formed of comparatively resilient metal, and also due to the fact that the U shape of the clamp causes the sides to come together as it is pressed upwardly. It will be apparent that in use, as shown in Fig. 2, the hand of the user will cause a pressure to be exerted between the enlarged portion or ridge 11 and the clamp 14, the greater pressure causing a greater gripping of the blade 12.

In the form of the invention shown in Figs. 5 to 8, inclusive, the structure is similar in every way to that disclosed in the above-mentioned figures, with the exception of the handle 15 which is here provided and the cut-out portion 16 of the ridge 11, which provides an easy means of adjusting the position of the blade. The handle 15 is made integral with the blade holder 10 and its provision provides means for holding the device. The clamp 14 acts in the same manner as described in Figs. 1 to 3, inclusive.

In the form of the invention shown in Figs. 9 to 11, inclusive, there is shown a form of the invention in which a holder 10 is formed of a

- single band of resilient metal and is provided with a ridge or shoulder 11'. At the lowermost ends of the holder and surrounding the same is pivoted a clamp 14' by means of a rivet 13' or the like.
- 5 A cut away portion is provided in the clamp adjacent the pivot as indicated at 17. In this form of the invention when the device is in open position as shown clearly in Fig. 10, the holder 10' is wedged within the opening 17 and the greater 10 the pressure placed upon the device in cutting with the blade, the greater the pressure of the holder upon the sides of the blade and therefore, the greater the grip thereof.

In all three forms of the invention herewith disclosed, it will be readily apparent that the clamps, being formed of comparatively rigid material as compared to the holders, will cause the holders to engage tightly around those portions of the blades with which they come into contact, 20 when the clamps are in engaged position, but that when the clamps are in disengaged positions, the blades may be easily moved from one position to another.

While but three forms of the invention have 25 been disclosed herein, it will be apparent to those

skilled in the art that the invention is not so limited but that various minor changes may be made therein without departing from the spirit thereof or the scope of the appended claims.

What is claimed is:

1. A blade holder comprising a blade gripping element of resilient material, the said blade gripping element having a cut out portion in its top rear side so that a blade can be adjusted horizontally in the blade gripping element, a handle 10 formed integral with the blade gripping element and a clamp pivotally mounted upon the said handle for gripping the open side of the blade gripping element for holding the blade in its adjusted positions.

15 2. A blade holder comprising a blade gripping element of resilient material, the said blade gripping element being formed in the shape of a looped band and adapted to grip one end of a blade, a clamp pivotally mounted upon the blade 20 gripping element, and the clamp having a cut out portion adapted to receive the blade and blade gripping element.
